WALTER H. COTTON, OF CHICAGO, ILLINOIS, ASSIGNOR TO UNION DRAFT GEAR COMPANY, OF CHICAGO, ILLINOIS, A CORPORATION OF DELAWARE.

DRAFT GEAR.

Application filed September 7, 1923. Serial No. 661,375.

The invention relates to draft gear for railway cars; and its objects are to secure reliability of action, high efficiency, and great strength in proportion to its weight.

5 The invention is fully hereinafter described, and is illustrated in the accompanying drawings, in which—

Fig. 1 is a longitudinal central plan view of the gear, details of the car structure being shown in plan;

10 Fig. 2 is a longitudinal central vertical section of the gear, showing it under compression, the rear end of a coupler being shown in elevation;

15 Fig. 3 is a longitudinal vertical section of the gear on the line 3—3 of Fig. 1, the gear being in normal position, the rear end of a coupler being shown in elevation;

20 Fig. 4 is a sectional view on the line 4—4 of Fig. 3;

Figs. 5, 6 and 7 are views in perspective of the friction elements of the gear;

25 Fig. 8 is a view in perspective of one of the followers; and

Fig. 9 is a transverse vertical sectional view showing a modified form of construction.

30 A pair of center or draft sills of a railway car are represented at 10, the draft lugs at 11, 11, and the buffing lugs at 12, 12. The coupler butt is shown at 13, and its extension or yoke at 14. All of these parts are of ordinary and preferred construction, and form no part of the invention.

35 The improved gear comprises a front follower 15, a rear follower 16, both of the chambered form and of such length that their inner ends meet when the gear is under full compression. The side, top and bottom walls of each of the followers are cor-

40 rugated, as shown at 17, 18, the corrugations extending transverse to the axis of the gear, and at least one of them being utilized, as hereinafter described, as a wedging element.

45 The followers are further strengthened by the formation on their outer surfaces of longitudinal ribs, as 19, at their inner ends being provided with a lateral outstanding flange 20, and at their outer ends with a

50 longitudinally extending flange 21. The end wall of each follower is provided with an inward depression along its vertical median portion, as shown at 22, strengthening webs, as 22^a, crossing this depression. The corru-

gations 17, 18, which are not utilized for 55 wedging action are preferably spanned by webs, as 23.

By the use of corrugations, ribs and flanges, and particularly of the first-named, the several walls may be comparatively thin 60 while adequate strength is obtained. The corrugations very materially increase the strength, though the walls may be made of uniform thickness.

The gear is of the friction plate type, comprising sets of intercalating plates interposed between friction members, some of which have a wedging action for compressing the plates—springs being provided for opposing the longitudinal movement of the 70 wedges and insuring their cooperation with the wedging surfaces with which they are associated.

65 The wedging elements are shown as taking the form of friction shoes 24 (Fig. 5), 75 and, as shown, are four in number, appearing plainly in Fig. 1, and being designated, respectively, 24, 25, and 26, 27, two of the shoes being housed in each follower and seated against its side walls, the outer face 80 of each shoe being provided with a vertical rib 28 in wedge form, such rib entering one of the corrugations, as 18, which constitutes the cooperating wedging element.

Housed within each of the followers, and 85 located on the axis of the gear, is a friction block 29, 30, shown in detail in Fig. 6. Each of these blocks is longitudinally channeled in its sides for the accommodation of springs, as hereinafter described, and each is 90 also socketed from its inner end in both its upper and lower portions, as shown at 31, 32, to provide seats for a pair of springs 33, 34.

95 The friction plates are arranged in four groups (Fig. 4) 35, 36, 37, 38, two on each side of the axis of the gear, two groups being above and two below its horizontal median line, the several groups being located between the friction shoes 24 to 27 and the 100 central blocks 29, 30, the adjacent faces of these elements being flat for frictional engagement with the contiguous plate.

105 Each group of friction plates consists of two sets, one set, as 39, normally extending from a short distance from the end wall of the follower 16, well into the follower 15, the other set, as 40, normally extending from a

short distance from the end wall of the follower 15 well into the follower 16, this arrangement being most plainly shown in Fig. 3. These plates are alike in form, one of them being shown in detail at 41 (Fig. 7).

The plates of the two groups on the same side of the gear are arranged in reverse order. As shown in Figs. 1 and 3, one of the plates of the set 39 in the lower group 38 (Fig. 4) is in contact with the shoes 24, 26, while in the upper group 37 (Fig. 3) one of the plates of the set 40 is in contact with these shoes. As there is an even number of plates in each group, as shown twelve, it follows that the inner plate of the upper group belongs to the set 40, and of the lower group to the set 39. The plates of the two groups on the opposite side of the gear are similarly arranged.

20 The shoes, the central friction block, and all of the friction plates associated with each follower are interlocked by means of cross-bars 42, 43, seated, respectively, in recesses 44 in the block 29, 45 in the several friction plates, and 46 in the two shoes, and recesses 47 in the block 29, 45 in the friction plates, and 48 in the shoes.

The width of the friction plates is such that there is left between the upper and lower groups at each side a spring pocket, the lateral channels in the friction blocks 29, 30 forming extensions thereof. Within each of these pockets is located a pair of springs, as 49, 50, and 51, 52, these springs reacting between seats associated with the two followers.

In the modification illustrated in Fig. 9, the cross plates 53, 54, which tie together the central friction blocks, the friction plates and the shoes are located above and below these elements, instead of adjacent to the springs 49, 52, as shown in Fig. 4.

A pair of tie-bolts 55, 56, are shown as passing centrally through the springs 33, 34, 45 the ends of the friction blocks 29, 30, and the end walls of the two followers. The function of these rods is to hold the gear in assembled form previous to installation. They may be left in the gear after installation, if desired.

Normally the parts occupy the positions shown in Fig. 1. On the application of either buffing or draft stresses one of the followers is moved toward the other, the initial movement being resisted mainly by the springs 49 to 52. The shoes, as 24, 25, of the advancing follower are carried forwardly with it, their advance being resisted by their frictional engagement with the plates, and consequently a wedging action occurs which forces the shoes inwardly, increasing this friction. The tie bars, as 42, 43, are carried forwardly with the shoes, advancing the friction blocks 29 with which they are associated, compressing the springs

33, 34, which urge backwardly the friction block and shoes associated with the stationary follower.

The ends of the friction plates which are associated with the advancing follower are presently encountered by the end wall thereof, and these plates are consequently advanced between the plates associated with the stationary follower. The friction plates associated with the latter follower are moved backwardly into engagement with its end wall by reason of the friction developed and then, remaining stationary, the other sets of plates are advanced between them. At its inner ends each of the friction plates 41 is recessed, as shown at 57, to afford clearance for the tie bars within the follower into which these ends of the plates project. The width of the recesses 45 in all of the plates is preferably sufficiently greater than the width of the tie bars so that the positive advancing movement of the plates is due to the engagement of the end wall of the associated follower with their inner ends.

In release the springs 49 to 52 urge backwardly the follower which has been advanced, relieving the wedging action upon the shoes and consequently reducing the friction between the various parts. The springs 33, 34, acting directly upon the central friction blocks, and through the tie bars, as 42, 43, upon the shoes, carry these parts backwardly, and, as soon as the tie bars encounter the outer ends of the slots 45 in the plates which have been advanced, carry these plates backwardly with them. The other set of plates are restored to normal position by the friction, and the central friction block and shoes associated with the stationary follower assume their normal positions by reason of the friction and the wedging action of the shoes under the influence of the outward pressure of the friction plates.

By reason of the arrangement of the friction plates of the upper and lower groups in reverse order, as described, the tendency of the outer plates of one of these groups to carry with it the shoe or central wedging element with which it is associated is opposed by the corresponding outer plate of the other group, which remains stationary.

While preferred forms of construction are shown, I do not desire to be restricted thereto, as any form which comes within the definition of the invention contained in the appended claims I regard as being within the scope thereof.

I claim as my invention—

1. In a draft-gear, a pair of oppositely arranged chambered followers having corrugated side walls, a group of friction plates within said followers, friction shoes having inclined faces engaging said corrugated walls

for compressing said plates, and resilient means for resisting inward movement of said followers.

2. In a draft gear, a chambered follower 5 having walls of substantially uniform thickness throughout, one of such walls being configured to form a plurality of corrugations, certain of said corrugations constituting wedging faces.

10 3. In a draft gear, a pair of followers, at least one thereof being chambered, having transverse corrugations in its side walls, and relatively movable shock absorbing elements interposed between the followers comprising an element having an inclined face 15 cooperating as a wedge with the inner face of one of the corrugations, resilient means for resisting the compression of said gear and acting directly on said followers for releasing the gear, and means for yieldingly resisting the inward movement of said elements upon the compression of said gear.

4. In a draft gear, a chambered follower having corrugated walls forming a plurality 25 of inclined faces, shock absorbing elements associated with the follower, said elements being relatively movable and frictionally engaging each other, one of such elements having a wedging face cooperating with one 30 of the inclined faces of the follower, and resilient means for resisting the inward movement of said followers and said last named element upon compression of the gear.

5. In a draft gear, in combination, a pair 35 of chambered followers, shock absorbing elements interposed between the followers and comprising a pair of centrally disposed friction blocks, shoes having wedging engagement with the side walls of the followers, 40 groups of relatively movable intercalating friction plates interposed between the friction blocks and the shoes, spring means interposed between and engaging said followers, and means for yieldingly resisting the 45 movement of said shoes during the compression of the gear.

6. In a draft gear, in combination, a pair 50 of chambered followers, shock absorbing elements interposed between the followers and comprising a pair of centrally disposed friction blocks, shoes having wedging engagement with the side walls of the followers, means for yieldingly resisting the inward movement of said shoes during compression 55 of the gear, groups of intercalating friction plates interposed between the friction blocks and the shoes, means for interlocking the shoes associated with each follower with one of the blocks and with one set of the plates of each group, and means for returning the parts to normal position after compression.

7. In a draft gear, in combination, a pair 60 of chambered followers, shock absorbing elements interposed between the followers and comprising a pair of centrally disposed fric-

tion blocks, shoes having wedging engagement with the side walls of the followers, means for yieldingly resisting the inward movement of said shoes during compression of the gear, groups of intercalating friction 70 plates interposed between the friction blocks and the shoes, transverse bars each engageable with shoulders on one of the blocks, one set of the plates of each group and on one pair of the shoes, and resilient means for resisting compression of said gear. 75

8. In a draft gear, in combination, a pair of chambered followers having wedging portions on their side walls, shock absorbing elements interposed between the followers and comprising a pair of centrally disposed friction blocks, shoes having wedging portions for engagement with the wedging portions of the side walls of the followers, each of said shoes having an extended friction surface in front of and at the rear of its wedging portion, groups of intercalating friction plates interposed between the friction blocks and the shoes, means for interlocking the shoes associated with each follower with one of the blocks and with one set of the plates of each group, and spring means interposed between the blocks. 85

9. In a draft gear, in combination, a pair 90 of chambered followers, shock absorbing elements interposed between the followers and comprising a pair of centrally disposed friction blocks, shoes having wedging engagement with the side walls of the followers, groups of intercalating friction 95 plates interposed between the friction blocks and the shoes, means for interlocking the shoes associated with each follower with one of the blocks and with one set of the plates of each group, spring means interposed between the blocks, and spring means interposed between the followers. 100

10. A draft gear comprising a pair of followers, central and outer friction elements associated with said followers, groups of intercalating friction plates interposed between the central and both outer friction elements, the two sets of plates of different groups being arranged in reverse order, means for compressing said plates on compression of said gear, and resilient means for returning the parts to normal position after compression. 110

11. In a draft gear, in combination, a friction member, two groups of intercalating friction plates cooperating with the same face of such member, the two sets of plates of the two groups being arranged in reverse order, and means for urging the groups of plates toward the friction member during compression of the gear, and resilient means to restore the parts to normal position after compression. 120

12. In a draft gear, in combination, opposed chambered followers each having 130

- wedging faces associated with its side walls, friction shoes associated with such side walls and having wedge faces cooperating with wedging faces thereof, a central friction element within each follower, an upper and a lower group of intercalating friction plates interposed between corresponding sides of the two central elements and the adjacent shoes, the two sets of plates of the upper and lower groups being arranged in reverse order, and means for forcing the friction shoes against and into frictional engagement with the plates, and for causing the relative movement of the friction plates.
13. In a draft gear, in combination, opposed chambered followers each having wedging faces associated with its side walls, friction shoes associated with such side walls and having wedge faces cooperating with wedging faces thereof, a central friction element within each follower, an upper and a lower group of intercalating friction plates interposed between corresponding sides of the two central elements and the adjacent shoes, the two sets of plates of the upper and lower groups being arranged in reverse order, and springs reacting between the two central elements.
14. In a draft gear, in combination, opposed chambered followers each having wedging faces associated with its side walls, friction shoes associated with such side walls and having wedge faces cooperating with wedging faces thereof, a central friction element within each follower, an upper and a lower group of intercalating friction plates interposed between corresponding sides of the two central elements and the adjacent shoes, the two sets of plates of the upper

and lower groups being arranged in reverse order, springs reacting between the two central elements, and bars interlocking the central element and shoes of each follower with one set of plates of the several groups.

15. In a draft gear, in combination, opposed chambered followers each having wedging faces associated with its side walls, friction shoes associated with such side walls and having wedge faces cooperating with wedging faces thereof, a central friction element within each follower, an upper and a lower group of intercalating friction plates interposed between corresponding sides of the two central elements and the adjacent shoes, the two sets of plates of the upper and lower groups being arranged in reverse order, springs reacting between the two central elements, bars interlocking the central element and shoes of each follower with one set of plates of the several groups, and springs reacting between the two followers.

16. In a draft gear, in combination, a pair of followers having wedging portions on their inner walls, shock absorbing elements interposed between said followers and comprising a pair of centrally disposed friction blocks, friction elements movable relatively to each other and to said blocks, shoes engaging said elements and having wedging faces for engaging said wedging portions, resilient means operating independently of said blocks for resisting the inward movement of said followers, and resilient means for resisting the inward movement of said shoes on the compression of said gears.

WALTER H. COTTON.
